UNITED STATES PATENT OFFICE.

ROBERT L. MYERS, OF NEW YORK, N. Y., ASSIGNOR TO PHINEAS B. MYERS, OF SAME PLACE.

DESIGN FOR A PAPER BOX.

SPECIFICATION forming part of Design No. 30,871, dated May 30, 1899.

Application filed May 8, 1899. Serial No. 716,026. Term of patent 7 years.

To all whom it may concern:

Be it known that I, ROBERT L. MYERS, of New York, (Brooklyn,) county of Kings, and State of New York, have invented and produced a new and original Design for Paper Boxes, of which the following is a specification, reference being had to the accompanying drawings, in which—

Figure 1 is a perspective view of my newly designed paper box, and Fig. 2 is a vertical transverse section of the same.

The leading feature of my design consists of a paper box representing a fireplace with a mantelpiece and stockings suspended therefrom.

a is the front of the paper box, slotted, as at *a*. Above the slot projects outwardly the flap *b*, from which depend the flaps *b'*. Below the slot *a'* is represented a fire-grate *c*, tongs *d*, and a coal-scuttle *e*. Above the flap *b* are ²⁰ represented vases *f* and a clock *g*. Within the box is contained a partition *h*, back of the open front *a*.

What I claim is—

The design for a paper box, substantially ²⁵ as herein shown and described.

ROBERT L. MYERS.
